CLAIM

The ornamental design for a chest of drawers, as shown and described.

DESCRIPTION

FIG. 1 is a top perspective view of a chest of drawers showing our new design;

FIG. 2 is a top plan view thereof;

FIG. 3 is a front elevation view thereof;

FIG. 4 is a side elevation view thereof, the opposite side being a mirror image thereof; and

FIG. 5 is a top perspective view of a chest of drawers showing a second embodiment of our new design;

FIG. 6 is a top plan view thereof;

FIG. 7 is a front elevation view thereof;

FIG. 8 is a side elevation view thereof, the opposite side being a mirror image thereof;

FIG. 9 is an enlarged sectional view taken along line 9—9 of FIG. 3; and,

FIG. 10 is an enlarged sectional view taken along line 10—10 of FIG. 3.

The rear and bottom views form no part of the claim designed. The subject matter shown in broken lines forms no part of the claimed design.
